EXPANDING JAW SCREW EXTRACTOR

Thomas C. Tedei, Franklin Park, Ill.

Application July 21, 1954, Serial No. 444,718

3 Claims. (Cl. 81—72)

This invention relates, in general, to screw extractors and extractors, and more particularly to a tool for removing the embedded parts of pipes, pipe nipples, bushings, solder bushings, broken pipe threads, and other parts, such, for example, as plumbing and steam fitting parts which have had their heads or outer portions broken or twisted without leaving a projection sufficiently long to enable removal in the usual manner.

The tool of the present invention is also adapted for use by mechanics, tool and die men, and elsewhere, as desired, for removing and/or applying other parts.

Devices of the character to which the present invention relates have usually consisted of a tapered operating portion provided with helical ribs for engagement with the metal or other material of the part to be extracted and disposed reversely with respect to the threads of said part with intermediate flutes or grooves therebetween. These tools have been open to objections; in the first place, one such tool has been adapted for use with only one size of pipe, pipe fitting, nipple, bushing or other threaded part. Therefore, for example, for seven or eight sizes of pipes, pipe fittings, nipples, bushings or the like, a corresponding number of such tools have been required. This increases the cost and introduces complications in selecting and accommodating the various sizes of tools to the various sizes of pipes, pipe fittings, nipples, bushings and the like.

In the second place, the strength of the aforementioned type of tools has not always been sufficient to enable them to resist the torsional stresses incident to normal use.

One of the main objects of the present invention is to provide an improved form of tool of the character described which is adapted for use with a relatively large number of different sizes of pipes, pipe fittings, nipples, bushings and the like and which may be more positive and certain in action as well as stronger than prior tools of the aforementioned character.

Another object is to provide a tool with which more force may be applied to the pipe, pipe fitting, nipple, bushing or the like for removing the same from the part into which it is screwed.

Another object is to provide a tool of this character which is less expensive for a plurality of pipes, pipe fittings, nipples, bushings and the like of different sizes and which is of simple and practical construction, efficient, easy and reliable in operation, relatively inexpensive to manufacture, and well adapted for the intended purpose.

Further objects and advantages of the invention will appear from the following detailed description taken in connection with the accompanying drawing showing one embodiment of the invention, it being understood that the invention is limited only within the scope of the appended claims and not to the particular embodiment selected for illustration.

In the drawing:

Figure 1 is a side elevational view of my improved extractor partially broken away and in section showing the jaws in closed position in full lines and with one jaw shown

2

in dotted lines in its open or separated position with respect to the other jaw;

Figure 2 is a top plan view taken on the line 2—2 of Figure 1;

Figure 3 is a bottom plan view taken on the line 3—3 of Figure 1;

Figure 4 is a fragmentary view of the left hand end of the device as shown in Figure 1 with the jaws separated and showing the manner in which the edges at the angles or corners of the stepped portions for one size of pipe, pipe fitting, nipple, bushing or other threaded part bite into the interior of such part for removing the same from a part into which it is screwed; and

Figure 5 is an end view taken on the line 5—5 of Figure 1 showing in dotted lines the jaws separated into engagement with the part to be removed and a wrench applied to the sides of the jaws intermediate the ends thereof for turning same to remove the threaded part.

Referring now to the drawing, the embodiment of the invention therein illustrated comprises a pair of jaws 1 and 2 each in the form of flat bar having opposite flat parallel sides 6—6, and intermediate flat top and bottom surfaces 7—7 normal or at right angles to the sides 6—6.

At the left hand end of the device as shown in Figure 1, the jaws 1 and 2 have stepped portions 8—8, 9—9, and 10—10 and at the right hand end the jaws have stepped portions 11—11, 12—12, 13—13, and 14—14. The stepped portions afford different size portions of substantially polygonal configuration for entry into different sizes of pipes, pipe fittings, nipples, bushings or other threaded parts. For example, the stepped part 14—14 may enter a tubular or hollow threaded part of $\frac{3}{8}$ " internal diameter whereas the stepped portions 13—13, 12—12, 11—11, 10—10, 9—9, and 8—8 may enter tubular or hollow threaded parts of $\frac{1}{2}$ ", $\frac{3}{4}$ ", 1", $1\frac{1}{4}$ ", $1\frac{1}{2}$ ", and $1\frac{3}{4}$ " internal diameter and the top and bottom surfaces 7—7 may enter a tubular or hollow threaded part of a larger internal diameter. The foregoing sizes and the number of different size parts with which the tool may be used are merely illustrative and the invention is not in any way limited to the sizes or the number of different size parts with which the tool may be employed.

Taking, for example, the stepped portions 8—8 which are shown in Figure 4 entered into a pipe, pipe fitting, nipple, bushing or other threaded part 15, these stepped portions 8—8 are of substantially polygonal configuration with edges 16 at the corners or angles thereof for biting engagement with the part 15 to be extracted. The other stepped portions and the intermediate portions of the jaws 1 and 2 are of similar polygonal configuration but of different sizes and have similar edges at the corners or angles thereof for biting engagement with parts of different sizes.

Means operable to separate the jaws 1 and 2 to expand the edges 16 of the polygonal stepped portions into biting engagement with the interior of the threaded part and to permit the jaws 1 and 2 to be closed or contracted for insertion and removal of the stepped portion from the part to be inserted or extracted comprises a pair of screws 18—18 having screwed or threaded engagement in openings 19—19 which open transversely through the jaw 1. The outer ends of the screws 18—18 have kerfs or polygonal sockets 21 for engagement therein, for example, of an Allen wrench for screwing the screws 18 inwardly or outwardly with respect to the jaw 1. The inner tapered ends 22 of the screws 18 are adapted by engagement with the surface 23 of the jaw 2 to separate this jaw from the jaw 1 to open position as shown in Figure 4 and in dotted lines in Figures 1 and 5. This expands the edges 16 of the stepped portions with great force into biting engagement with the interior of the part 15. Then, for example, with a flat crescent wrench or other suitable wrench applied to the flat sides of the intermediate portions of the

jaws 1 and 2 as shown at 22 in Figure 5 these jaws are turned about the axis of the stepped portions to screw the part 15 into or from the part with which it has threaded engagement.

The opposed jaw surfaces at 23 are preferably offset laterally from the opposed end surfaces 24 to form on the jaw 2 a tenon-like lateral projection 25 which is guided for sliding movement in a mortise-like cavity 26 in the jaw 1. The ends of the tenon-like projection 25 by cooperation with the jaw 1 at the ends of the mortise-like cavity 26 maintain the jaws properly related and take such end thrusts as may be imposed.

Guide pins 28-28 have tight pressed fit or are otherwise fixedly secured at 29 in openings in the jaw 1 and extend loosely through openings 30 in the jaw 2 and guide this latter jaw in its opening and closing movements.

Separation of the jaw 2 from the jaw 1 is limited by engagement of the head 31 of a pin 32 with the inner end 33 of a socket 34 in the jaw 2. When the jaws are closed, the outer end of the head 31 is substantially flush with the bottom surface 7 of the jaw 2. The pin 32 extends loosely through an opening in the jaw 2 for sliding movement of this latter jaw thereon. The opposite end of the pin 32 is further reduced and screwed at 35 into a threaded opening in the jaw 1. The head 31 of the pin 32 has a kerf or polygonal socket 36 for engagement therein, for example, of an Allen wrench for screwing the threaded end of the pin 32 into the jaw 1.

The jaws 1 and 2 according to the present invention are adapted to be cut from steel bars, for example, by a drop forging operation or they may be machined to shape if desired. Upon completion of the jaws, they are preferably tempered in an oil tempering bath to case harden the jaws. The guide pins, stop pin, and screws 18 may also be case hardened.

The use of flat bars facilitates forming the jaws and these bars provide the sharp edges 16 at the corners of the polygonal shaped stepped portions which provide effective and improved biting engagement with the part to be inserted or extracted when the jaws are opened with powerful force by the screws 18. The tool is quickly adaptable to pipes, pipe fittings, nipples, bushings and the like of different sizes and for such part of any size the tool is engaged therewith expeditiously and with great force for effective and certain action.

The embodiment of the invention shown in the drawing is for illustrative purposes only and it is to be expressly understood that said drawing and the accompanying specification are not to be construed as a definition of the limits or scope of the invention, reference being had to the appended claims for that purpose.

I claim:

1. A screw extractor comprising a pair of flat jaws rectangular-shaped in transverse section and having coplanar

flat sides arranged to be gripped by a wrench for turning said jaws about the longitudinal axis thereof, said jaws having at one end stepped down portions affording different size portions rectangular-shaped in transverse section for entry into externally threaded tubular parts of different sizes and having angular edges for internal engagement with the tubular part, screw means carried by one of said jaws for engagement endwise with the adjacent surface of the other jaw to separate said other jaw from said one jaw and thereby expand said angular edges of said stepped down portions into biting engagement with the interior of said tubular part, guide pin means carried by said one jaw and extending into an opening in said other jaw to guide said other jaw in its movement away from and toward said one jaw, and a stop pin carried by said one jaw and extending into an opening in said other jaw and provided with an enlarged head engageable with said other jaw to limit separation of said other jaw from said one jaw.

2. A screw extractor according to claim 1 wherein one of the jaws has a tenon-like projection having sliding movement in a mortise-like cavity in the other jaw to maintain said jaws in alignment and take such longitudinal thrusts as may be imposed on said jaws.

3. A screw extractor comprising a pair of flat jaws rectangular-shaped in transverse section and having coplanar flat sides arranged to be gripped by a wrench for turning said jaws about the longitudinal axis thereof, said jaws having at one end stepped down portions affording different size portions rectangular-shaped in transverse section for entry into externally threaded tubular parts of different sizes and having angular edges for internal engagement with the tubular part, screw means carried by one of said jaws for engagement endwise with the adjacent surface of the other jaw to separate said other jaw from said one jaw and thereby expand said angular edges of said stepped down portions into biting engagement with the interior of said tubular part, and pin means carried by said one jaw and extending into openings in said other jaw to guide said other jaw in its movement away from and toward said one jaw and to limit separation of said other jaw from said one jaw.
